IRONING APPARATUS

Willy Schmieglitz, Berlin, Germany, assignor to
Heinrich Kellner G. m. b. H., Dresden, Germany, a company of Germany

Application May 3, 1934, Serial No. 723,696
In Germany January 29, 1934

2 Claims. (Cl. 219—19)

This invention relates to an electric ironing apparatus which is particularly intended for the ironing of trousers. The new apparatus replaces ironing with a flat-iron by pressing the trousers between electrically heated pressplates. These plates are formed and arranged in such a way that the seams of the trousers are not pressed but lie free in grooves in the apparatus.

The new apparatus consists of a base-plate and two upper pressing plates which fold over and after insertion of the trousers are pressed from above on to the latter. The pressing plates and also the base-plate have in their interior electrical heating wires or a special electrical heating element which heats the trousers, previously dampened, and after a few minutes produces a perfect crease without any work at all.

In the drawing one form of construction of the object of the invention is shown by way of example.

Fig. 1 shows the apparatus opened.

Fig. 2 shows the apparatus in use.

Fig. 3 is a rear-view of the apparatus.

Fig. 4 is a cross-section through a heating element.

Fig. 5 shows the plug connection arrangement.

Fig. 6 shows the unbreakable heating wire connection.

The base plate of the apparatus, which is made in the shape of a pair of gentlemen's trousers, consist of two parts, 1 and 2, which have a gap for the seams of the trousers and are connected together at the rear. Each of the parts is fitted with an electrical heating element 3 or 4; to the parts 1 and 2 of the base-plate are fitted the folding pressing plates 5 and 6, which are likewise fitted with electrical heating elements 7 and 8 respectively. The heating elements can either be placed inside or mounted on the plates. The current is supplied by the cable 9 which is connected to an electric light point. The cable 9 is connected with an intermediate plug-socket 10, which is provided with pin-sockets on both sides, these being intended to accommodate the plugs 11 and 12. These plugs are arranged in cavities in the plates 1 and 2 and connected electrically with the heating element wires.

The parts 1 and 2 correspond in shape to a pair of trousers, while the plate 1 is cut away to a curve 13 which runs exactly against the seam of the seat of the trousers. The corner of the part 2 is also cut away to a curve. The distance between the two parts 1 and 2 is greater at the top than at the bottom, so that none

of the seams is pressed during the ironing and crushed and also shiny spots are avoided.

For purposes of ironing the trousers are placed in the open apparatus, brushed with a damp brush and pressed by closing down the pressing plates 5 and 6, with the aid of the rod 14. If the cable 9 is then connected to a source of current the trousers will then be ironed in about 5 to 10 minutes. Either each trouser leg can be ironed separately or both legs can be ironed at the same time.

The parts 1 and 2 can either be rigidly joined together or else joined so as to be detachable. For travelling models it is advisable to make these two parts detachable. For this purpose the parts 1 and 2 have rings 15 on their rear sides, in which the retention rods 16 are inserted. These rods are fitted with handles 17 and bent portions 18, so that when they are turned by 90° they are firmly wedged against the plates and ensure rigid connection of the latter. The construction of the heating element can be seen from Fig. 4. The heating wires 19 are embedded in corrugated board 20, in the grooves of which they cannot move. The heating wires are insulated wires, but over the same there is provided a layer of oilskin, over which flannel or a similar material is stretched. The heating element formed in this way is very light in weight and is glued on to the plates 1, 2, 5 and 6, which could advantageously be made of plywood.

It is advantageous for the heating elements 4 and 8 to form a common circuit which is arranged in parallel with the circuit of the paired heating elements 3 and 7 with the aid of the adapter socket 10. The ends of the heating elements are led to the plugs 11 or 12, which are sunk into the plates and secured there by means of screws.

The heating wires, which run parallel to each other from top to bottom and then from the bottom to the top again, pass over from the rigid base-plate to the folding pressing plates. In order to prevent the breaking of the wire at the point where it passes from the base-plate to the pressing plate, when the latter is repeatedly opened and closed, the arrangement shown in Fig. 6 has been adopted. The ends of the adjacent heating elements 4 and 8 are brought out of the plates and twisted together and if necessary soldered together. The twisted end lies between the base-plate 2 and the pressing plate 5, so that when the latter is opened or shut the wire is not pinched between two plates and the risk of the wire breaking is eliminated.

The advantages of the new apparatus are due to the fact that it is not possible for the seams to be pressed in any way, owing to the shape and the grooves of the base-plate and the pressing plates. In addition the cost of manufacture is so small that the apparatus can be put on the market at a low price.

I claim:—

1. Electric trouser presser and ironer comprising two rigidly connected electrically heated plates, said plates having excisions to accommodate the seat seam and recesses accommodating the leg seams, said leg seam recesses increasing in width in the direction of the crotch, other plates of identical shape and form connected to the first mentioned plates, by means of

hinges, said latter plates being likewise electrically heated, eyes in the plates, rods having bent portions passed through said eyes, said rods being turned 90° to clamp said plates together and handles for turning said rods.

2. In an electric trouser presser and ironer as claimed in claim 1, electric resistances composed of wires carried by the plates for heating the same, a source of electricity, the resistance wires lying in the same plane and parallel to one another, said wires being equidistantly disposed for uniformly heating all parts of the trousers, and a cable connecting said resistances with the source of electricity.
